DESIGN FOR A TEXTILE FABRIC

Hugh J. Carragher and Thurston B. Wilson,
Brooklyn, Conn.

Application August 10, 1938, Serial No. 79,230

Term of patent 3½ years

To all whom it may concern:

Be it known that we, Hugh J. Carragher and Thurston B. Wilson, citizens of the United States, residing at Brooklyn, in the county of Windham, State of Connecticut, have invented a certain new, original, and ornamental Design for a Textile Fabric, of which the following is a specification, reference being had therein to the accompanying drawing, forming part thereof.

The drawing is a face view of a portion of a textile fabric, showing our new design.

We claim:

The ornamental design for a textile fabric, substantially as shown.

HUGH J. CARRAGHER.
THURSTON B. WILSON.
